SHAPING MACHINE

Fred G. Waller, East St. Louis, Ill.

Application March 21, 1934, Serial No. 716,604

5 Claims. (Cl. 113—38)

This invention relates generally to shaping machines, and more specifically to an improved shaping machine adapted for use in producing from blanks of metal and other bendable materials articles of the general shape of cans, cups, containers, etc., the predominant object of the invention being to produce an improved machine in the use of which one of the various articles of the description mentioned may be produced during a 10 single continuous operation of the machine.

Prior to this invention cans, cups, containers, and various other articles of this general nature were each produced by subjecting the blank of material being shaped to produce the article to successive, independent die operations; that is to say, the blank was subjected to the operation of one set of dies by which it was partially shaped, after which the blank was successively subjected in turn to a plurality of additional independent 20 die operations, each of which carried the shaping of the blank a step forward. This method of procedure is cumbersome and time-consuming, inasmuch as it calls for a transfer of the blank being operated upon from one to another set of dies as the shaping operations progress. Also, it is expensive because of the necessity that considerable equipment be produced and maintained on hand for carrying out the various independent shaping operations.

In view of the foregoing I have devised a single machine which functions in such manner that the article being formed is completely produced by the improved machine during one continuous operation. Thus the expense of producing and 35 maintaining a plurality of sets of independent dies is eliminated, and the time required for producing articles in accordance with this invention is very much less than was the case when the articles were produced in accordance with the 40 independent die method formerly followed.

Fig. 1 is a vertical section of the improved machine, a part thereof being broken away to conserve space.

Fig. 2 is a fragmentary, vertical section of the machine shown in Fig. 1 but with parts thereof shown in changed positions.

Fig. 3 is an inverted plan view of the machine as shown in Fig. 1.

Fig. 4 is a horizontal section taken on line 4—4 of Fig. 1.

Fig. 5 is a fragmentary detail illustrating the cam for actuating the ejecting mechanism of the machine.

Fig. 6 is a fragmentary view of one of the cams

of the machine which actuates shaping elements of the machine.

Fig. 7 is a view similar to Fig. 2, but showing the forming elements of the machine as they appear when the forming operation has been 5 completed.

In the drawings, wherein is shown for the purpose of illustration, merely, one embodiment of the invention, A designates the improved shaping machine generally. The machine A includes a 10 main body portion 1 which may be of any desired shape and dimensions, said body portion being shown in the drawings as more or less cylindrical and the hollow interior thereof providing a circular cavity 2 in which certain important 15 parts of the machine are disposed. Also the main body portion 1 of the machine is provided with a slot 3 formed transversely through the wall portion thereof, through which material from which the articles being produced with the aid of the 20 machines is passed into, through, and out of the machine. The slot 3 is formed continuously through the body portion 1 of the machine, and said slot is open at opposite sides of the main body portion of the machine, the intake end of the slot 25 being indicated by the reference character 1a and the discharge end of the slot being designated by the reference character 1b. As will presently appear herein, the sheet of material M being operated on by the machine is fed into the machine 30 through the intake end of the slot 3, and said sheet is discharged from the machine through the discharge end of the slot 1b, said sheet in the meantime having blanks stamped therefrom which are formed by the machine into the articles 35 being formed.

Arranged within the lower portion of the cavity 2 of the body portion 1 of the machine A is a plurality of annular forming elements 4. These annular forming elements 4 are nested one within 40 the other, as shown clearly in the drawings, the outer face of the largest annular forming element being in contact with the face of the cavity 2, and the faces of adjacent forming elements being in contact with each other. The innermost or 45 smallest forming element 4 differs from the other forming elements 4 in that the opening formed therethrough is of irregular shape, this opening having a tapering portion at its upper end designated by the reference character 5, which communicates with a portion 6 located immediately below said tapering portion, and this portion 6 is of less diameter than a portion 7 disposed beneath and in communication with said portion 6. The largest forming element 4 has a cutting edge 55

8 located at the junction of its outer face and its top edge, and this cutting edge co-operates with an annular cutting edge 9 at the junction of the upper edge of the slot 3 and the inner face 5 of the cavity 2, so as to cut blanks B from the sheet of material M as it passes through the machine. The annular forming elements 4 are movable vertically with respect to each other, and the largest outer forming element is movable 10 vertically with respect to the face of the cavity 2.

Disposed immediately above the group of annular forming elements 4 is a similar group of annular forming elements 10. The forming elements 10 correspond in number to the forming 15 elements 4, and said two groups of forming elements are arranged in such relation that each forming element 4 has a forming element 10 arranged above it in precise, vertical alignment with respect thereto. As is the case with the forming 20 elements 4, the forming elements 10 are capable of moving vertically with respect to each other. Also, the outer or largest element of the group of forming elements 10 is movable vertically with respect to the face of the cavity 2.

25 Downward movement of the forming elements 10 relative to each other and with respect to the main body portion 1 of the machine A is limited by a pair of pins 11. The outer end portions of these pins are disposed in openings 12 formed 30 in the main body portion 1, and said pins pass through aligned, vertically extended slots 13 formed through the forming elements 10. The pins 11 are supported at their inner ends by a hollow post 14 provided with apertures 15 which 35 receive the inner end portions of said pins, said hollow post being suitably supported in a fixed position by a stationary element 16 forming a fixed part of the machine. The lower portion of the hollow post 14 is disposed within the opening 40 formed through the smallest annular forming element 10, the outer face of said post contacting closely with the face of said opening, and at the lower end of the post an opening portion 17 is provided which is of greater diameter than 45 the opening 18 formed through the remainder of the post and is of tapered formation.

The pins 11 prevent the annular forming elements 10 from moving downwardly beyond the point where the lower edges thereof are aligned 50 horizontally with the upper edge of the slot 3, as when the annular forming elements are so positioned the top faces of the slots 13 contact with the pins and thereby prevent further downward movement of the forming elements. Also, 55 because the slots 13 are disposed vertically and are elongated the forming elements 10 may move upwardly considerable distances without hindrance from the pins 11.

At the lower end of the machine A a plurality 60 of shafts 19 is arranged radially with respect to the main body portion of the machine, as shown most clearly in Fig. 3. The shafts 19 are supported for rotation in suitable bearings 20 which are supported by, or form parts of, the main body 65 1 of the machine. At the inner end of each of the shafts 19 a cam 21 is located which is provided with a plurality of cam faces 22^a, 22^b, 22^c, 22^d, 22^e, 22^f, 22^g, and 22^h, there being one of such cam faces of each cam 21 in contact with the lower face of each of the annular forming elements 4. In other words, the corresponding cam faces of the various cams 21 contact with the same forming element at different points thereof. The cam faces 22 of each cam 21 are arranged in 70 spaced relation in the direction of the circum-

ference of the associated shaft 19, as shown clearly in Fig. 6, this spacing of the cam faces 22 being such that the said cam faces move the annular forming elements 4 upwardly in successive relation. In other words, if Fig. 6 be considered, the 5 cam 21 is rotated in the direction indicated by the arrow, and the first movement resulting from the rotation of the cam is that cam face 22^a moves the outermost or largest annular forming element upwardly. As the cam face 22^a is moving the 10 outermost forming element upwardly, the cam face 22^b of the rotating cam 21 starts to move the second largest forming element upwardly. Then in turn the cam faces 22^c, 22^d, 22^e, 22^f, 22^g, and 22^h impart upward movement to the forming 15 elements in successive order from the larger elements to the smallest, innermost element, as shown in Figs. 2 and 7. When the cams 21 have moved the forming elements 4 upwardly as described, and the high points of the cam faces 20 thereof have passed beyond the lower faces of the forming elements, said forming elements move downwardly by gravity in contact with the cam faces of the various cams 21 to the positions in which the forming elements are shown in Fig. 25 1, whereupon the continuously rotating cams 21 again move the forming elements upwardly as explained.

At the top of the body portion of the machine A a plurality of radially disposed shafts 23 are 30 arranged, which are similar in arrangement to the shafts 19 at the lower end of the body portion 1, said shafts being rotatably supported in suitable bearings 23'. At the inner end of each of the radially arranged shafts 23 is located a cam 35 24, these cams being similar to the cams 21 at the lower end of the body portion of the machine. The cams 23 are each provided with cam faces 24^a, 24^b, 24^c, 24^d, 24^e, 24^f, 24^g, and 24^h which 40 are adapted to contact with the top faces of the annular forming elements 10, these cam faces being arranged in spaced relation in the direction of the circumference of the associated shaft 23 in the manner already explained in connection with the cam faces of the cams 21. The operation 45 of the cams 24 is so correlated with the operation of the cams 21 that the cam faces of the cams 24 move into contact with the top faces of the various annular forming elements immediately as the cam faces of the cams 21 contact with and 50 start to move the annular forming elements 4 upwardly, and as the high points of the cam faces of the cams 21 move toward the lower faces of the forming elements 4, the high points of the cam faces of the cams 24 move away from the 55 top faces of the annular forming elements 10. Thus each pair of vertically aligned, annular forming elements during vertical movement thereof is interposed between cam faces which contact with the bottom face of the lower forming element and top face of the upper forming element.

One of the shafts at the lower end of the body portion 1 includes an extended portion 25 to which a bevel gear 26 is fixed. Also, said extended shaft portion has fixed to it inwardly of 60 the bevel gear 26 a gear 27 which meshes at its opposite sides with gear idlers 28, said gear idlers 28 in turn meshing with gears 29 that are fixed to shafts 30 mounted in suitable bearings 31. The shafts 30 have fixedly mounted thereon bevel 65 gears 32 which mesh with bevel gears 33 fixed to the two radially arranged shafts 19 other than the shaft 19 with which the extended shaft portion 25 is associated. The bevel gear 26 is arranged in mesh with a similar bevel 70

gear 34 which is fixed to a vertically disposed shaft 35 that is arranged in suitable bearings 36.

The radially arranged shafts 23 located at the top of the body portion 1 of the machine A are driven by gearing arranged precisely as is the gearing just described for driving the radially arranged shafts 19, and therefore such gearing need not be described in detail. In other words, the shaft 35 is provided at its upper end with a bevel gear 37 which meshes with a bevel gear 38 mounted on an extension 39 of one of the radial shafts 23. Also, this shaft extension 39 has fixed to it a gear 40 which through the operation of suitable gearing and shafts similar to those described in connection with the radial shafts 19 drives the shafts 23.

Fixedly mounted on the shaft extension 39 is a cam 41 which imparts vertical movement to a rod 42 that is supported in a suitable bearing 43. The rod 42 is connected by a slot and pin connection to an end of an arm 44 which is pivoted to a fixed support 45, the opposite end of said arm being connected by a slot and pin connection to the upper end of an ejector rod 46 which is arranged for vertical movement within the hollow post 14. The ejector rod 46 at its lower end is provided with an enlarged head 46', and also a coil spring 47 is associated with the arm 44, said coil spring being connected at its opposite ends to the arm and a fixed part of the machine, whereby upward movement of the end of the arm to which the rod 42 is attached is resisted.

In the operation of the machine A a blank of material M is fed into said machine through the inlet end of the slot 3, and the upward movement of the outer annular forming element 4 will cause the cutting edge 8 thereof and the cutting edge 9 within the cavity 2 to cut a circular blank B from said sheet of material. The annular forming elements 4 moving upwardly in response to rotation of the cams 21, as already explained herein, bend the portion of the blank beyond the central portion B' thereof upwardly, as shown in Figs. 2 and 7, this upward movement of the blank portion being performed by the upwardly moving, annular forming elements 4 and 10 between which the portion of the blank being bent is interposed. When the portion of the blank B beyond the central portion B' thereof has been bent upwardly until said portion embraces the lower end of the post 14, as shown in Fig. 7, the forming of the article has been accomplished, and at this time the high point of the cam 41 will contact with the lower end of the rod 42. This causes the arm 44 to be moved about its pivot, whereby the ejector rod 46 is moved downwardly so as to force the forward article downwardly from the machine through the opening within the innermost or smallest annular forming element 4. It is plain that one of the articles being produced is formed at each complete revolution of the cams 21 and 23, and it is likewise plain that the sheet of material M from which the blanks B have been cut is discharged from the discharge end of the slot 3.

I claim:

1. A shaping machine comprising a body portion provided with an opening through which a sheet of material is fed into the machine, cutting means within said body portion for cutting blanks from said sheet of material, a pair of groups of nested forming elements arranged within said body portion above and below said sheet of ma-

terial for forming said blanks into articles of the desired shapes, and means for imparting independent movement to the forming elements of said groups in such manner that the forming elements of each group are moved varying distances, and said forming elements of said pair of groups being moved in the same direction. 5

2. A shaping machine comprising a body portion provided with an opening through which a sheet of material is fed into the machine, cutting means within said body portion for cutting blanks from said sheet of material, a pair of groups of nested annular forming elements arranged within said body portion above and below said sheet of material for forming said blanks into articles of the desired shapes, and means for imparting independent movement to the forming elements of said groups in such manner that the forming elements of each group are moved varying distances, and said forming elements of said pair of groups being moved in the same direction. 10

3. A shaping machine comprising a body portion provided with an opening through which a sheet of material is fed into the machine, cutting means within said body portion for cutting blanks from said sheet of material, a pair of groups of nested annular forming elements arranged within said body portion above and below said sheet of material for forming said blanks into articles of the desired shapes, said annular forming elements being arranged one within the other, and means for imparting independent movement to the forming elements of said groups in such manner that the forming elements of each group are moved varying distances, and said forming elements of said pair of groups being moved in the same direction. 15

4. A shaping machine comprising a body portion provided with an opening through which a sheet of material is fed into the machine, cutting means within said body portion for cutting blanks from said sheet of material, a pair of groups of nested annular forming elements arranged within said body portion above and below said sheet of material for forming said blanks into articles of the desired shapes, said annular forming elements being arranged one within the other, and cam means for imparting independent movement to the forming elements of said groups in such manner that the forming elements of each group are moved varying distances, and said forming elements of said pair of groups being moved in the same direction. 20

5. A shaping machine comprising a body portion provided with an opening through which a sheet of material is fed into the machine, cutting means within said body portion for cutting blanks from said sheet of material, a pair of groups of nested annular forming elements arranged within said body portion above and below said sheet of material for forming said blanks into articles of the desired shapes, said annular forming elements being arranged one within the other, means for imparting independent movement to the forming elements of said groups in such manner that the forming elements of each group are moved varying distances, and said forming elements of said pair of groups being moved in the same direction, and ejecting means for discharging articles from the machine after they have 25

been produced from said blanks. 30

FRED G. WALLER.
